UNITED STATES PATENT OFFICE.

FRANK E. BESSLER, OF AKRON, OHIO.

INNER TUBE.

Application filed November 17, 1919. Serial No. 338,594.

To all whom it may concern:

Be it known that I, FRANK E. BESSLER, a citizen of the United States, residing at Akron, in the county of Summit and State 5 of Ohio, have invented a new and useful Inner Tube, of which the following is a specification.

This invention relates to improvements in inner tubes for tires, the object of the 10 invention being to provide an improved spring tube that is adapted to take the place of the ordinary inflatable tube.

A further object of the invention is to 15 provide a spring inner tube of the class described, the spring being formed of a plurality of sections which may be individually removed and replaced without the necessity of removing the entire spring.

A further object of the invention is to 20 provide improved means for controlling the expansion and contraction of the spring.

With the foregoing and other objects in view, which will appear as the description proceeds, the invention consists in the novel 25 features of construction and combination of parts which will be more fully described hereinafter and particularly pointed out in the claim.

In the drawings accompanying and forming part of this specification,

Figure 1 is a longitudinal section of a portion of a wheel illustrating the application of the present improved tire thereto;

Figure 2 is a cross section thereof, taken 35 on the line 2—2 of Figure 1;

Figure 3 is a diagrammatic view illustrating the means for controlling the expansion and contraction of the spring;

Figure 4 is a fragmentary view of a 40 fabric member that is interposed between the inner tube and the casing of the tire;

Figure 5 is a fragmental side elevation, partly in section, showing the abutting ends of the bands and Figure 6 is a plan, partly 45 in section, showing the relative relation existing between the ends of the parts of the bands.

Referring to the drawings, 2 designates the felly of a wheel, which is provided with 50 the usual clincher rim 3 for attachment of the tire casing 4.

The inner tube in the present instance 55 comprises a plurality of members 5 formed of spring steel, each disposed at an acute angle to the axis of the tire, as shown in Figure 1. For maintaining the spring

members 5 in position, I provide a pair of annular steel bands 6 extending circumferentially of the wheel, said bands preferably having both sides thereof of convex form. Each band may be divided into three parts 200 having abutting ends 100, each end carrying a pin 101 received removably in a recess 102 in the other of said ends. The abutting ends of the parts 200 of the bands at opposite sides of the tire are disposed in alternating order as shown in Figure 6, this construction facilitating the assembling of the device. The spring members 5 are each provided with a pair 70 of openings at each end thereof, and these openings are adapted to register with a pair of openings in the band 6 for the passage of split fastening devices 7 that are provided with enlarged heads, shown in 75 dotted lines in Figure 2, for engaging the spring members 5, said fastening devices being turned over at the inner ends on the bands 6, as clearly shown in Figures 1 and 2.

For controlling the expansion and retraction of the tube, I have provided a plurality of transversely extending shafts 8, each of which is threaded at its opposite ends with right and left hand threads respectively, 80 and the bands 6 are provided with threaded openings for engagement with such threaded ends, so that when the shafts are rotated, the bands will be drawn inwardly toward each other or pushed outwardly 85 away from each other, according to the direction of rotation of the shafts, thereby expanding or contracting the tube. For rotating the shafts 8, a sprocket wheel 9 is secured to each of such shafts approximately at the middle of its length, over which passes an endless chain 10, whereby on the rotation of one shaft all of the remaining shafts will be rotated. This arrangement is shown diagrammatically in 90 Figure 3. There may be nine of these sprocket wheels, three being carried by each pair of the parts 200 of the bands. One of the sprocket wheels 9 is provided with an enlarged hub, on one side of which is formed 95 a bevel gear 11. An approximately U-shaped bracket 12 is provided with an opening adjacent the end of each leg thereof through which the shaft 8 passes, the ends of such legs being offset inwardly into contact with the opposite sides of the hub of the sprocket wheel 9. The horizontal por-

tion of the U-shaped member or bracket is provided with an opening adapted to form a bearing for a stem 13, carrying at its inner end a bevel pinion 14 meshing with 5 the bevel gear 11. It will thus be seen that by winding the stem 13 the bevel gear 11 will be rotated, and by means of the sprocket and chain connection all of the shafts 8 will be rotated, thereby screwing the ends of 10 the shafts into the openings in the bands 6 or withdrawing them therefrom, so that said bands and the spring members 5, the ends of which are secured to the bands, are drawn inwardly to contract the tube or 15 forced outwardly to expand the same. The stem 13 projects through a tube 15, which tube is screwed into the rim 3 and projects through the felly 2 in a manner similar to the valve stem of a pneumatic tire, and is 20 provided at its outer end with an interiorly threaded cap 16. The outer end of the stem 13 is squared, as shown at 17, and a key 18 having a squared socket is provided for turning the same.

25 In the present instance a flexible cushion 19 is interposed between the spring members and the casing, this cushion being preferably formed of three plies of material cross-stitched together, as shown in Fig. 4. The 30 cushion 19 thus entirely encloses the spring members and not only prevents injury to the casing by such members, but serves to keep water out of the inner tube in case the casing is defective.

35 From the foregoing it will be seen that because of the fact that the spring members are disposed at an acute angle to the axis of the tire these members are longer than if they were disposed in a plane at right 40 angles to the axis of the tire, thus producing a more resilient tire as well as forming a brace for the whole inside of the tube that will distribute the pressure equally around

the wheel. It will also be seen that in case of the breakage or distortion of any of the 45 spring members such distorted member or members may be easily removed without disturbing the others, since it is merely necessary to remove the fastening devices 7 from the ends of the spring members. A 50 further advantage inherent in the structure herein described is that any side blow that the tire may receive is sustained by the bands 6, which are supported against such blows by the shafts 8. 55

While I have described in detail the structure herein illustrated, it is to be understood that I do not thereby limit my invention to the precise features shown, as I am aware that many mechanical changes 60 may be made therein without departing from the spirit and scope of the invention as set forth in the appended claim.

Having thus described my invention, what I claim is:—

In a device of the class described, a tubular resilient member embodying circumferential bands and transverse spring strips secured to the bands, screws having their ends threaded in opposite directions directly into the bands and housed therein, means for transmitting motion from screw to screw, a U-shaped bracket mounted on one screw, a shaft journaled in the base portion of the bracket, and beveled pinions 70 connecting the shaft and said screw, both of the pinions being located within the bracket, and being held in mesh thereby.

In testimony that I claim the foregoing as my own, I have hereto affixed my signature in the presence of two witnesses.

FRANK E. BESSLER.
